STRIP CUTTING DEVICE

Raymond R. Ward, Cleveland, Ohio

Application December 26, 1939, Serial No. 310,865

5 Claims. (Cl. 164—36)

My invention relates to linoleum strip cutters and in particular to cutters which may be used to utilize the unused pieces of linoleum which are usually discarded.

5 The means for utilizing these waste pieces is the main object of my invention.

Still another object is to recut strip linoleum to smaller widths for trims and insets.

10 These and other objects may be noted from the following specification and its accompanying illustrations, in which:

Fig. 1 is a top plan view of the device.

Fig. 2 is a side elevation of Fig. 1.

Fig. 3 is an end elevation.

15 Fig. 4 is a sectional view on lines 4—4 of Fig. 1.

Again referring to the illustrations; a U-shaped base 10 is recessed or slotted as at 11 the full length of said base. A plurality of apertures 12 are provided adjacent each end of said base and 20 are spaced at fixed or desired intervals as illustrated in Fig. 1 specifically, the top rail 10a of the U-shaped base 10 being shorter than the bottom rail 10b of said base, the projecting outer ends 13 and 13a of said base being shouldered at 14 and 14a to form a stop.

25 A plurality of bores or recesses 15, 16 and 17, through the top rail 10a, retain balls or bearings 18 therein which are held in position by flexible spring covers 19 pivoted at 20 on the top surface of the top rail 10a. A bore or recesses 21 through the bottom rail 10b also retains therein a ball or bearing 18a which is secured therein by a spring cover 19a pivoted at 20a on the bottom surface of the bottom rail 30 35 10b of the base 10.

An adjustable laterally sliding guide 22 is mounted within the recess 11 between the rails, pins 23 securing said guide in the position desired when apertures 24 in the opposite ends of 40 said guide register with apertures 12 in the bottom rail 10b of the base 10 as shown in Fig. 1.

45 A groove 25 in the front surface and adjacent one end of the bottom portion 10b of the base 10 has mounted therein a separating guide 26 secured to said bottom base portion 10b by a set screw 27.

50 Inwardly therefrom is an angular slot 28 in the front surface of said base portion 10b, while diagonally therefrom is a second angular slot 29 in the top portion 10a of the base 10, said slots 55 registering upon a diagonal plane.

A very thin cutting blade 30 is mounted within the angular slots 28 and 29 with the cutting edge 30a towards the center of the device. A pair of blade mounting or holding plates 31 and 32 are

secured to the top and bottom portions 10a and 10b, over the blade 30, by pairs of set screws 33 and 34, for the holding plates 31 and 32.

An adjustable guide 35 is mounted within a slight recess 36 in the top surface of the top 5 portion 10a, said guide is slotted at 35a for a sliding adjustment when the set screw 37 is released.

A stepped roller 38 is mounted on a pin 39 and is secured in place to the underside of the outwardly projecting end of the guide 35 by a nut 40 screwed upon the threaded end of said pin.

10 A mounting block 41 may be used to secure the device to a table or the like when in use.

In operation, the linoleum strip 42 is inserted 15 within the recess 11 from the right side and drawn along therein past the spring pressed bearings or balls 18 and 18a, which act as tensioning devices on the linoleum strip, until its forward edge contacts the blade edge 30a. 20

The inner edge of the linoleum strip 42 is 25 pressed against the laterally sliding guide 22 which has been adjusted to the desired width by registering certain of the apertures 24 at each end of the slide guide 22 with other apertures 12 at each end of the bottom portion 10b of the base 10. The pins 23 secured therethrough hold the slide guide 22 in proper alignment with relation to the linoleum.

The linoleum strip 42 is drawn forward from 30 right to left, the blade 30 cutting through the strip 42 which is parted by the separation guide 26.

I claim:

1. A strip cutting device comprising a U- 35 shaped member forming upper and lower rails with a space between the same, an adjustable guide mounted between the rails, spring pressed tensioning balls in the upper and lower rails, a cutting blade mounted on the rails, and a separating guide behind the cutting blade.

2. A strip cutting device comprising a U- 45 shaped member forming upper and lower rails with a space between the same, an adjustable guide mounted between the rails, spring pressed tensioning balls in the upper and lower rails, a cutting blade diagonally mounted in recesses in the face of the rails and a separating guide behind the cutting blade.

3. The combination stated in claim 1, said 50 blade being held in place by blade holding members mounted on the rail faces.

4. The combination stated in claim 1, and a further guide mounted in a recess in the upper surface of the device and having a roller extend- 55

ing outwardly past the face of the rails and engaging the outer edge of the material.

5. A strip cutting device comprising a U-shaped member forming top and bottom rails, the top rail being narrower than the bottom rail, a plurality of apertures formed in each end of the upper surface of the bottom rail, a laterally movable guide having holes in its respective ends

and a pin passing through a hole in the end of the guide and into one of the apertures of the bottom rail to hold the guide in a selected position, spring pressed tensioning devices mounted in both the top and bottom rails, a cutting blade mounted on the rails and a separating guide mounted behind the cutting blade.

RAYMOND R. WARD.
